MICROPOTENTIOMETER

Myron C. Selby, Boulder, Colo., assignor to the United States of America as represented by the Secretary of Commerce

Original application June 29, 1951, Serial No. 234,166, now Patent No. 2,782,377, dated February 19, 1957. Divided and this application February 8, 1957, Serial No. 639,152

2 Claims. (Cl. 333—27)

This invention relates to the development of a high-frequency low-voltage standard which will supply accurately known voltages from 1 to 10^6 microvolts at all frequencies from zero to several thousand megacycles without the use of attenuators. The present invention is a division of application Serial No. 234,166, filed on June 29, 1951, now Patent No. 2,782,377.

Presently employed systems for obtaining high-frequency low-voltage standards generally contemplate, for example, producing a high-frequency voltage of approximately one volt, attenuating such voltage and monitoring such voltage with a voltmeter. Such system presents several serious disadvantages. One is that the output impedance of the generator varies greatly over wide frequency ranges. A second disadvantage is the necessity of using attenuators to drop the generated voltage from the order of magnitude of one volt to all desired lower values—in this case, a ratio of 1 million to one. The construction of these attenuators, maintenance of their stability with regard to time, use, temperature, and humidity, and their calibration entail expensive and difficult procedures. A third disadvantage is the uncertainty of the initial calibration and especially of long-time calibration stability. Still another reason for inaccuracy is the effect of load on the frequency of the generator.

As a result of these limitations, considerable difficulty 40 has been encountered in establishing low-voltage, high-frequency standards.

It is therefore the primary object of this invention to provide a voltage standard for low voltages at high frequencies that will be free from the aforementioned difficulties.

Another object is to provide a high-frequency, low-voltage standard that will operate over a range of frequencies from about 30 to several thousand megacycles and over a range of voltages from one to one million 50 microvolts.

A further object is to provide a standard with a non-inductive output impedance.

A still further object is to provide a standard with an output impedance of the order of milliohms.

Still another object of the invention is to provide an inexpensive and uncomplicated high-frequency, low-voltage standard.

Another object is to provide a balanced voltage standard at high frequencies and low voltages.

A still further object is to provide a standard that is not sensitive to frequency.

Still another object is to provide a standard that is quickly and easily calibrated.

Still another object is to provide a high-frequency, low-voltage standard that is calibrated by the use of a direct current.

Another object is to provide a standard with a good long-time stability.

In accordance with the present invention there is provided a unit which will hereinafter be referred to as a coaxial micropotentiometer, which unit will when used

2

in conjunction with a radio-frequency oscillator and voltmeter provide the standard output microvolts and millivolts required. The micropotentiometer is composed of three principal parts, a noninductive low-value resistor, a uniform coaxial waveguide section, and an R-F voltmeter. The waveguide terminated by the noninductive resistor acts as a load on the R-F oscillator and the standard voltage is taken off across the resistor. The resistor is made of a very thin annular ring of conductive material and is connected between the center and outer conductors of the coaxial waveguide. Since such type of resistor is essentially noninductive, its resistance will remain constant over a very wide frequency range, and therefore the direct-current resistance can be taken as resistance at high frequency without introducing an appreciable error. It should also be noted that since this resistor is made of highly conductive material its resistance will be very low. As a result, when the micropotentiometer is being used to calibrate an instrument whose input impedance is relatively high, the instrument will represent practically no increase in load and therefore the frequency of the R-F oscillator feeding energy to the micropotentiometer will not vary significantly during the application of the instrument. At any given frequency the high-frequency current flowing through this resistor is accurately determined from the measured high voltage input into the coaxial waveguide and the length of this guide.

The micropotentiometer therefore includes a resistor that does not vary with frequency and a means for measuring the load current which is also unaffected by frequency. Then by means of Ohm's law ($E=IR$) the value of voltage is easily calculated, or obviously, low voltage output of the instrument may be calibrated in terms of its high voltage input. It is not necessary to compute the current entering the resistor because the low-voltage output is theoretically precisely equal to

$$V_s \frac{R_r}{Z_0} \csc \beta_0 l \quad (1)$$

Here V_s is the high R-F input voltage to the waveguide, R_r is the resistance of the disk, β_0 is the known phase constant of the waveguide at the given frequency, and l is the length of the waveguide.

It is apparent from the above that the only function of the R-F oscillator is to provide a readily controllable current at a known frequency. Indeed any radio-frequency oscillator, or signal generator, may be used as a source. Since the load on the oscillator remains practically constant, frequency stability is readily obtainable. Also since the voltage is measured at the micropotentiometer the oscillator is only required to produce a controllable amplitude. Expensive calibration of the oscillator and attenuators is eliminated entirely. Microvolts and millivolts of the same order of accuracy as in available high-voltage voltmeters are readily obtained, and errors approaching 100% and higher are safely eliminated. Variations in calibration over long periods is no longer a serious problem since, even if the resistance of the annular ring does vary, which is highly unlikely, the resistance of the annular ring can be measured by the very rapid and uncomplicated D-C voltmeter-ammeter method.

Other uses and advantages of the invention will become apparent upon reference to the specification and drawings in which:

Fig. 1 is an elevational view of a preferred embodiment of the invention;

Fig. 2 is a cross section of a clamped annular ring type of assembly;

Fig. 3 is a cross-sectional view of a modification of

Fig. 2 in which the annular ring is deposited by plating, firing, evaporation, or other means;

Fig. 4 shows a modification of the annular ring assembly in which the annular ring or resistor lies in the output plane of the waveguide; and

Fig. 5 is a block diagram showing the micropotentiometer according to this invention being used to calibrate a vacuum-tube voltmeter.

Referring specifically to Fig. 5 which is a block diagram showing a micropotentiometer embodying the features of this invention being used to calibrate a vacuum-tube voltmeter, the general operation of the instant invention is as follows: The signal generator 1 provides a current which is adjustable both as to frequency and amplitude for the micropotentiometer 2. The adjustable current is obtained by varying the current output of the oscillator of the signal generator. Most standard signal generators have an adjustment of this type and therefore there is no need for the use of attenuators. This immediately eliminates the many problems incident to the use of attenuators, some of which were pointed out in the introduction.

The adjustable current is fed into the micropotentiometer comprising the present invention where it is measured by a means to be described later, and its value is indicated by an indicating instrument such as the vacuum-tube voltmeter 3. In connection with the present modification an auxiliary vacuum-tube voltmeter 4 may be employed to measure the output of the micropotentiometer.

The resistance of the micropotentiometer, which is constant for any single resistive unit, may be of any desired value from 1000 microhms to 1 milliohm or higher if necessary, depending upon the value of voltage desired. This D.-C. resistance is accurately measured before the start of the standardizing procedure by the D.-C. voltmeter-ammeter method generally used for measuring very low resistances. This method requires the use of accurate D.-C. ammeters and voltmeters which, however, are relatively inexpensive since the currents and voltages used are relatively large. The voltage output can then be easily calculated by Equation 1. For example, if it is desired to obtain voltages of one to 100 microvolts at a given frequency one may use a resistance element of one milliohm, a waveguide section $\frac{1}{4}$ of a wavelength long having a characteristic impedance of 100 ohms and input voltages of 0.1 to 10 volts. Other combinations could of course also be used. This example demonstrates the extreme ease with which it is possible to obtain standard voltages by means of the present invention.

Fig. 2 is a cross-sectional view detailing the construction of the waveguide and annular resistor assembly of the micropotentiometer according to this invention. As indicated, the micropotentiometer resistor assembly includes a generally coaxial waveguide comprising an outer conductor member 31 and an inner conductor 27. The resistor assembly 19 is connected to one end of the waveguide as shown in Fig. 1 to form a coaxial micropotentiometer.

The resistive element 11 which is formed of an annular ring of highly conductive material is connected between the outer conductor 31 and the inner conductor 27. The calibrated voltage is developed across the annular ring 11 and appears as the output which is taken between the conductors 31 and 27.

The micropotentiometer resistance element shown in Fig. 2 is about 3 inches long and 2 inches in diameter. Other sizes and shapes have been used, some of which are shown in Figs. 3 and 4 and will be referred to later in the specification. The micropotentiometer resistance element also includes a center post 18 having a flange or shoulder 26. The center post 18 provides a coaxial connecting means for the inner conductor 27 of the coaxial waveguide assembly. In the embodiment disclosed in the present application no current-responsive device

such as the thermocouple 9 disclosed and claimed in applicant's above-identified patent is employed.

The conductive annular ring 11 is slidably mounted over the center post 18 and rests against the flange 26. The annular ring is held fast against the flange by means of a hollow cylinder 27 which fits snugly around the post 18 and is held tightly against the ring 11 by means of a nut 21. A circular disk 28, which is composed of a suitable insulating material, fits around the cylinder 27 and seats against a shoulder 30 forming part of the cylinder. A nut 29, which screws onto the cylinder 27, holds the insulating disk firmly in place. The subassembly containing the parts 18, 11, 27, 21, 28, and 29 fits into an outer hollow cylinder 31. The outer portion of the insulating disk 28 seats against a flange 32 forming part of the cylinder 31 and is held tightly against this flange by a nut 33. It will be noted that the disk 28 provides the only mechanical connection between the inner and outer portions 27 and 31 of the unit (except for the annular ring 11). The disk 28 therefore provides for a strong mechanical connection but one that is electrically nonconductive. Except for this disk and the annular ring the inner and outer portions of the assembly are separated by the air space 34.

The micropotentiometer resistance assembly shown in Fig. 2 also includes an output connector 20 comprising a sleeve 35 and threaded flange 35a which is screwed down into the cylinder 31. To prevent this part from coming into contact with the annular ring 11 and possibly tearing it because of the twisting motion of 32 while it is being screwed into place, a washer 36 is placed between the disk and the part 32. A lead washer (not shown) may be placed between 11 and 36 to insure a better electrical contact if desired. This unit is now complete and is adapted for mounting in the transmission line 51 (Fig. 1) by means of the screw threads 31a on the outer surface of the cylinder 31. For this purpose, the transmission line 51 (Fig. 1) may be provided with a rotatable collar 52 to facilitate connecting the micropotentiometer resistance assembly (or element).

In the completed unit 19 the annular ring 11 provides the only electrical path between the inner conductor or center post 18 and the outer conductor or cylinder 31. As shown in Figs. 2 and 3 the resistor element 11 comprises a thin, planar annulus. In practice this annular ring may be made in several ways and from a number of different materials depending upon the desired resistance. These annular rings can be made of foils of platinum, tin, silver, gold or any other conductive material, having thicknesses of the order of 0.0003 to 0.001 inch, and having resistances ranging from 100 microhms to several milliohms. Also carbon elements have been made with resistances of about 1 ohm, and if required even higher resistances can be used. Actually the resistance of the ring depends upon several facts; such as, the resistivity of the material, the thickness of the ring, and the ratio of the inner and outer diameters of the ring. The main feature of these annular rings is that they are made of conductive elements and therefore must be kept exceedingly thin to get the desired resistances. This feature is very important because the annular rings must be kept as thin as possible so that the current will penetrate the entire thickness of these rings at all desired frequencies. The higher the frequency the thinner must be the element. The allowable thickness of the rings is inversely proportional to the square root of the frequency. It was anticipated and found to be true during the development of this invention, that if the above conditions were met the inductance of the rings would be extremely small and even at the very high frequencies the reactance drop may be ignored without introducing an appreciable error.

Fig. 3 shows a modification of the assembly 19 in which the annular ring 11a is made by plating rather than by forming circular disks out of the appropriate conductive foil. The cylindrical insulator 28a provides the mechani-

cal connection between center post 18a and the outer conductor of cylinder 31a. The insulator 28a may be made of steatite or glass. If either is used, the following process for joining the insulator and metal may be used. Silver paint is fired onto the inner and outer cylindrical surfaces of the insulator 28a. The silver is copper flashed so as to protect the silver. The copper surfaces are then tinned. Also the surfaces of the post 18a and conductor 31a that will contact the insulator are tinned. Then the post 18a and conductor 31a are soldered to the insulator. So far only the mechanical connections between 18a, 28a, and 31a have been made and nothing has been done toward the plating of the annular ring.

The plating process for the annular ring 11a may be as follows: The surface of conductor 31a lying in the plane A—A of the annular ring and a small portion of the center post 18a lying to the left of the insulator are silver plated. Then a very thin film of silver is evaporated over the entire surface formed by the conductor 31a and insulator 28a in a plane perpendicular to the longitudinal axis of the micropotentiometer resistance assembly. Then another and final silver finish is plated over this entire surface. This silver finish provides the annular ring 11a.

There are other methods of forming the assembly 19 and the annular ring 11. If the post 18 and conductor 31 are made of Kovar metal they can be sealed in glass and therefore the insulator 28 would be glass. Then to form ring 11, fine silver can be deposited right on top of the glass. Also it is well known that metals can be soldered to ceramics and so the unit 19 might be made that way. Insulating cements might also be used.

Many other similar techniques are known or are being developed, but since this forms no part of the present invention they will not be discussed.

As previously stated, one of the major objectives of this invention is to provide a source of standard voltage that has a negligible internal impedance. This becomes increasingly difficult with the unit shown in Fig. 2 as the frequency increases because the inductance of the output connector begins to have noticeable effect at these higher frequencies. In Fig. 3 it will be noted that the annular ring 11 is not in the output plane P—P of the micropotentiometer. In practice this ring lies about one centimeter to the right of the output plane. Therefore at higher frequencies the impedance of this section of the connector (10 ohms at 1000 megacycles) causes a noticeable difference between the standard voltage at plane A—A and the voltage at the output plane P. This difference, of course, will depend to a great extent on the input impedance of the unit being calibrated.

To obviate this difficulty micropotentiometer resistors have been developed in which the annular ring lies in the output plane. Such an arrangement is shown in Fig. 4. The output connector 31a is modified so that one surface of the insulating support 68 for the center post 58 is located in the output plane P—P. The annular ring 11a is plated over the insulating support 68 and over the entire surface of the output connector in the output plane P.

This embodiment of the invention can be used over the entire range of from zero to several thousand megacycles without encountering any serious frequency effects as explained above.

The over-all construction of the embodiment of the invention in this case is shown in Fig. 1. The micropotentiometer comprises a known length of coaxial transmission line 51 terminated in an annular ring assembly 19 of one of the types shown in Figs. 2, 3 and 4. The R-F input cable is indicated at 50, while the vacuum tube voltmeter probe for the circuit set-up described in connection with Fig. 5 is shown at 55.

In one form, the coaxial transmission line is made equal to an odd number of quarter wavelengths of the frequency of the input. For a line with negligible losses (this is usually true in practice) the output voltage across the annular ring is equal to the input voltage times the ratio of

the annular resistance to the characteristic impedance of the line. The equation for this relation is

$$V_2 = V_1 \frac{R}{Z_0} \text{ volts} \quad (2)$$

where:

V_1 is the input voltage,

V_2 is the output voltage,

10 R is the resistance of the annular ring in ohms, and Z_0 is the characteristic impedance of the line in ohms.

As indicated by Equation 2, it is necessary to know the input voltage in this form of micropotentiometer. However, in this instance such restriction does not present a difficult problem, since the input voltage is of the order of magnitude of one volt. The characteristic impedance of coaxial transmission lines may be 100 ohms. When used with an annular resistance of 1 milliohm the term R/Z_0 has a value of 10^{-5} . Therefore to obtain a voltage as low as 10 microvolts, an input voltage of one volt is used. Vacuum-tube voltmeters that will measure one volt even at very high frequencies are readily available.

It must be remembered, however, that Equation 2 holds true only when the length of the coaxial line is equal to an odd number of quarter wavelengths of the impressed frequency.

25 However, the output voltages at intermediate frequencies may be computed from the Equation 1 above which can also be rewritten as

$$30 V_2 = V_1 \frac{R}{Z_0} \csc Kf \text{ volts} \quad (3)$$

where:

V_1 is the input voltage

V_2 is the output voltage

35 R is the resistance of the annular ring in ohms

Z_0 is the characteristic impedance of the line in ohms

K is a constant equal to $2.09 \times 10^{-8}l$, l being equal to the length of the line in meters for an air dielectric line.

40 In case the line has a solid dielectric having a dielectric constant of K relative to air, the value of l has to be multiplied by the square root of K.

f is the applied frequency in cycles per second.

Again the ratio of R to Z_0 is so small that the input 45 voltage can be relatively large. Obviously Equation 3 can also be written as

$$46 l = \frac{V_2 Z_0}{V_1 R \csc K' f} \quad (3a)$$

50 where K' is equal to 2.09×10^{-8} for air.

It will be apparent that the embodiments shown are only exemplary and that various modifications can be made within the scope of my invention as defined in the appended claims.

55 What is claimed is:

1. An adjustable amplitude constant-voltage source for producing accurately controllable voltages over a wide frequency range comprising a coaxial transmission line, a source of radio frequency current having a voltage V_1 applied to one end of said transmission line, a micropotentiometer resistance assembly in the form of a waveguide connected to the other end of said transmission line, said micropotentiometer resistance waveguide assembly comprising coaxial center and outer input elements connected

60 respectively to corresponding elements of said coaxial transmission line and having coaxially arranged output terminals corresponding respectively to said input terminals for connection to a load, a resistor electrically joining and coaxial with the center and outer coaxial input elements of said micropotentiometer resistance assembly, said resistor comprising a thin, planar annulus of conductive material having a finite resistance R, the magnitude of which is of an order which is negligible compared to the impedance of the load to which said output terminals are

connected, the thickness of said annulus being inversely proportional to the square root of the highest frequency employed to permit complete current penetrations through the thickness of said annulus throughout said frequency range, the length of said coaxial transmission line being predetermined in accordance with the equation:

$$l = \frac{V_2 Z_0}{V_1 R \csc K' f}$$

where:

V_2 corresponds to the output voltage,
 V_1 corresponds to the voltage of said applied radio frequency current,
 R is the resistance of said thin planar annular resistor,

15 Z_0 is the characteristic impedance of said coaxial transmission line, K' is a constant determined by the dielectric material in said coaxial line being 2.09×10^{-8} for air, l is the length of said transmission line in meters, and f is the frequency of said applied radio frequency current; and means for determining the voltage input to said one end of said coaxial transmission line.

5

K' is a constant determined by the dielectric material in said coaxial line being 2.09×10^{-8} for air, l is the length of said transmission line in meters, and f is the frequency of said applied radio frequency current; and means for determining the voltage input to said one end of said coaxial transmission line.

2. The invention of claim 1 in which said resistor lies in the plane of the output terminals of said constant-voltage source.
